UNITED STATES PATENT OFFICE

170,342

VENETIAN BLIND COVER

Marion E. Skwark, Binghamton, N. Y.

Application October 3, 1951, Serial No. 16,814

Term of patent 14 years

(Cl. D21—6)

To all whom it may concern:

Be it known that I, Marion E. Skwark, a citizen of the United States of America, residing at Binghamton, county of Broome, and the State of New York, have invented a new, original, and ornamental Design for a Venetian Blind Cover, of which the following is a specification, reference being had to the accompanying drawings, forming a part thereof.

Portions of the Venetian blind cover are lined to indicate transparency.

I claim:

The ornamental design for a Venetian blind cover, substantially as shown and described.

MARION E. SKWARK.
